(57) **CLAIM**

We claim the ornamental design for a bracelet, as shown and described.

DESCRIPTION

FIG. 1 is a perspective view of a bracelet, showing our new design in a closed configuration;

FIG. 2 is a front elevational view of FIG. 1;

FIG. 3 is a rear elevational view of FIG. 1;

FIG. 4 is a left-side elevational view of FIG. 1;

FIG. 5 is a right-side elevational view of FIG. 1;

FIG. 6 is a top plan view of FIG. 1;

FIG. 7 is a bottom plan view of FIG. 1;

FIG. 8 is another perspective view of the bracelet in FIG. 1, showing our new design in an open configuration;

FIG. 9 is a bottom plan view of FIG. 8, the top plan view being a mirror image thereof;

FIG. 10 is a left-side elevational view of FIG. 8;

FIG. 11 is a right-side elevational view of FIG. 8;

FIG. 12 is a front elevational view of FIG. 8; and,

FIG. 13 is a rear elevational view of FIG. 8.

The broken lines showing a person's wrist FIG. 1 depict environmental matter and form no part of the claimed design.

1 Claim, 7 Drawing Sheets
